UNITED STATES PATENT OFFICE.

CHARLES BEEBEE, OF RAVENSWOOD, NEW YORK.

CAR-COUPING.

SPECIFICATION forming part of Letters Patent No. 267,823, dated November 21, 1882.

Application filed April 27, 1882. (No model.)

To all whom it may concern:

Be it known that I, CHARLES BEEBEE, of Ravenswood, in the county of Queens and State of New York, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical section. Fig. 2 is a bottom plan. Fig. 3 is a perspective view of the sliding block detached, and Fig. 4 is a perspective view of an improved link used preferably in combination with my improved coupling.

Similar letters of reference indicate corresponding parts in all the figures.

My invention relates to that class of draw-heads which will couple automatically; and it consists, first, in the construction of the draw-head, and, second, in the construction of an improved guiding-link, substantially as herein-after more fully described, and pointed out in the claims.

In the drawings, A is the draw-head, which has a longitudinal recess for the insertion of the link, as usual. The top *a* and bottom *b* of this recess are parallel to each other, the bottom having a longitudinal slot, *c*, and a perforation, *d*, which latter corresponds to a similar perforation in the top plate, *a*, (denoted by *d'*.)

In the rear part of the rectangular recess formed by plates *a* and *b* is placed a rubber spring or cushion, B, against which works the back of the slide C. The latter consists of a square or rectangular block, made of wood or metal, either solid or hollow, cut off or beveled at its front end, as shown at *e*, and having a recess or pocket, *f*, beneath this bevel for the insertion of the link. The slide-block C may be provided with rollers *g*, so as to slide easier within its recess, and has a central lug or eye, *h*, which projects down through the slot *c*, and serves the double purpose of a guide to the block and a means of attachment for the chain D, which passes forward, under the coupling, over a pulley, *i*, and has a rod, *k*, terminating in a weight, E, secured to its end.

F is a beveled or wedge-shaped piece, secured in the mouth or front end of the coupling, so as to fit against the beveled face of the slide C, thereby preventing it from sliding forward too far, impelled by weight E. To prevent jar-ring or oscillation of the latter, it is secured at the end of a rod, *k*, which slides vertically in a sleeve, *m*, projecting from a downward-projecting arm, G, bolted to the under side of plate *b*, and which carries also the lug or brackets *n*, in which pulley *i* is pivoted.

The pin H fits loosely into the perforations *d* *d'*, and is steadied in its up and down movements by a perforated guide piece or sleeve, *o*, affixed upon the top of plate *a*. The perforation *d'* in the top plate, *a*, extends down through the rear part of the beveled piece F, as shown, so that when the pin is inserted into the hole ready for coupling (which position is indicated in dotted lines in Fig. 1) it will rest against the bevel *e* of slide C, which is then in its forward position—viz., abutting against the piece F.

My improved link, which is used in combination with this coupling, consists of a link, I, of the ordinary shape and construction, secured upon the middle of which, so as to cross or intersect it at right angles, is a double bail or guide piece, (denoted by K,) having perforations *p* at each end, through which the guide-rod L is inserted. The latter terminates in a head or handle, *l*, as shown in Fig. 4.

From the foregoing description the operation of my improved coupling and link will be readily understood. The link, being inserted into the pocket *f* of slide C, will be kept in a horizontal position, so as to readily enter the mouth of the coupling next to it. By using my improved link the brakeman, standing on the front platform of the car, may, by means of the sliding guide-rod L, so adjust the projecting part of the link that it shall enter a coupling at uneven height, this rod permitting him to hold the link at an oblique or slanting position, either up or down, according to whether the draw-head to which it is to be coupled is higher or lower. The moment the cars are brought together the slide C will be pushed back, and as soon as the bevel *e* has passed the hole *d'* the pin will, of its own weight, fall down into its coupled position, (in-

dicated in full line in Fig. 1.) A chain or rod may be secured to the head of pin H, so that this may readily be withdrawn from the platform or roof of the car when the cars are to be uncoupled. The rubber cushion B will prevent any sudden shock or jar while the cars are being coupled or while in motion.

Having thus described my invention, I claim and desire to secure by Letters Patent of the United States—

1. In a car-coupling, the combination, with the slotted draw-head A, having the cushion B and beveled stop F, of the block C, sliding between the cushion and stop, provided with the rollers g g, link-pocket f, and having the bevel e, to permit it to project with its front

end under the beveled stop F, so as to bring the entrance to the link-pocket flush or in a line with the front end of said stop, substantially as shown and set forth. 20

2. The link I, having the vertical bail or guide-bracket K and sliding guide-rod L, substantially as and for the purpose hereinbefore set forth.

In testimony that I claim the foregoing as my own I have hereunto affixed my signature in presence of two witnesses.

CHARLES BEEBEE.
